UNITED STATES PATENT OFFICE.

HERMAN S. CAHEN, OF CLEVELAND HEIGHTS, OHIO.

INDICATING DEVICE.

Application filed February 19, 1927. Serial No. 168,619.

This invention relates to automatic indicating devices for use in connection with sewing machines or the like, as for instance a machine for sewing together the sections 5 of a book.

In the operation of a machine for sewing together the sections of a book, according to the well-known practice, the attendant feeds the sections successively into the machine from the stack in which the sections are grouped according to the number and arrangement intended for a particular book. The number of sections varies, of course, for different books, but the number should be 10 the same for all books in the same piece of work. It is possible, however, that there will be too few or too many sections in some individual groups of sections that are to be sewed together. And it is this possible error 15 that it is desirable to have automatically called to the attention of the operator so as to avoid the sewing and later binding of an imperfect book.

It is therefore the object of the present 20 invention to provide such a device for indicating to the operator whether the prearranged groups of book sections contain the proper number of sections.

More specifically, it is the object of my 25 invention to provide such a means in the form of an attachment which can be applied to the sewing machine already in use and hence without requiring any modification of the sewing machine structure.

30 A still further object consists in so constructing such a device that it can be adjusted or set according to the number of sections per book in the particular piece of work, and can also be reversed or re-set 35 after the sewing operation has been started.

Still further objects will be apparent from the following description and claims when considered together with the accompanying drawing.

40 Fig. 1 is a side elevation of my improved attachment; Fig. 1^a is an enlarged detail view illustrating a portion of the book-sewing mechanism to which the present invention is applied; Fig. 2 is a front elevation 45 thereof; Fig. 3 is a detail view taken on line 3-3 of Fig. 2 and shows the parts in one position; and Fig. 4 is a view similar to Fig. 3 but showing the parts in the succeeding position.

45 The main bracket 1 of my attachment is adapted to be secured to the end of the well-

known form of book-sewing machine by means of screw bolts 2 which already form part of the sewing machine frame 3. Fixedly mounted on the inner side of the bracket 1 is the stud bearing 4 upon which is rotatably mounted the gear 5 with its hub on its inner side. This gear 5 is operated by pinion 7 which is rotated intermittently by pawl 7'. This pawl is carried by the 50 rock arm 8 which receives its rocking movement from the cross bar 9. The bar 9 is that part of the book-sewing machine which moves the heads up and down and is sometimes referred to as the "head-motion bar". 55 The rock arm 8 is clamped upon the bar 9 by means of screws 11. The pawl 7 is engaged by spring 12 and has an adjustable stop screw 13. Thus, for each and every upward movement of the bar 9, the pinion 7 and the gear 5 are moved the extent of one tooth; and, since each upward movement of bar 9 corresponds to the stitching operation for each individual book section, it will be seen that the number of sections fed into 60 the machine and stitched will be represented by the number of teeth the gear 5 is turned. The gear 5 is held in its successive positions by the locking pawl 15 which is mounted upon a stud shaft in the upwardly 65 extending arm 16 of the bracket 1. A spring 15' is provided for pawl 15. The weight 17 is suspended from the cord or cable 18 which is attached at its one end to the hub of gear 5 and extends over the sheave 19 mounted 70 on bracket 1. The intermittent movement of gear 5 winds up the cord or cable 18, thereby creating a potential force for reverse 75 automatic operation of the gear 5 at the proper moment, as will be now explained. 80 The direction of winding movement is indicated by arrow in Fig. 3.

Gear 5 is provided with a trip pin 20 which is screwed or otherwise secured in one of the series of holes 21 in the gear 5. This pin is adapted to engage the depending finger 22 on the lower end of the rockably mounted bar 23, the upper end of which serves as a striker for the bell 24. This bell is mounted on the upper extension 25 of the upright portion 26 of the bracket 1. The pin 20 is set in the proper hole according to the number of sections in the particular book to be sewed, and this action takes place automatically when the gear 5 has 100 been advanced the number of teeth corresponding thereto. The bar 23 is rockably 105 110

mounted upon the stud shaft or bearing 27 on the upright portion 26 of the bracket, there being permitted a slight movement of this bar about the axis of the shaft 27, limited by adjustable stop screw 28, and there being permitted also a slight movement in a plane at ninety degrees to that of the rocking movement just referred to. There is sufficient play in the mounting of this bar 10 to permit such combined movements, and the purpose of the same will now be explained. There is also an adjustable stop 26^a.

The coil spring 29 has one end fastened to the lower part of the bar, as at 30, and is anchored at its other end to the upright portion 1^a of the bracket. This spring extends diagonally so as to tend to pull the bar 23 both laterally and rearwardly. During the intermittent movement of gear 5, the lateral 20 pull of spring 29 holds the bar 23 in such position that its lower end portion is free of the detent 31 which is here shown as being screw-threaded and hence adjustable in the upright portion 26. Under such condition, the screw 32, which extends through the lateral extension 33 of the lower end of bar 23, is in idle position and permits the pawl 15 to engage with the teeth of gear 5, in the manner above described. But when 30 pin 20 engages the downwardly extending portion 22 on the lower end of bar 23, as will happen when the gear 5 has been given the predetermined number of intermittent movements, the bar 23 is rocked about the shaft 35 27 and the upper end of bar 23 is moved away from the bell so as to be set for later striking and ringing the same. This rocking movement is sufficient to cause the screw 32 to engage and raise the pawl 15 out of engagement with the teeth of gear 5 and to move the shoulder or edge 35 past the end of detent 31, whereupon the combined rearward and lateral pull of spring 29 causes the shoulder or edge 35 to engage detent 31 40 and to thereby hold the screw 32 in raised or active position against the under side of pawl 15. The radius of the lower portion of bar 23 is of proper length to permit this action of screw 32. The gear 5, being no longer held against reverse movement, is now released to the action of the weight 17, with the result that the gear 5 is instantaneously rotated in reverse direction, as indicated by arrow in Fig. 4, until the inclined 50 or cam member 36 engages the portion 22. The cam member 36 is so constructed and arranged that its engagement with the portion 22 causes the same to move towards the gear 5 and thereby causes the shoulder 35 to move out of engagement with the detent 31 with the assistance of spring 27^a; and the lateral pull of spring 29 at once causes the bar 23 to rotate on its axis so that the upper end thereof strikes and rings the bell. 60 Screw 32 is at the same time returned to

lower or idle position and the lower portion of bar 23 extends across the end of detent 31. The pin 37 on gear 5 is so positioned that it will engage the fixed stop 38 on the upright portion of the bracket, which engagement takes place immediately upon the actuation of the portion 34 by the cam member 36. The parts are then again in position shown in Figs. 1 and 3.

It is to be understood that the pawl 7', 75 during its backward movement, is out of engagement with its pinion 7 and hence will permit reverse rotation of pinion 7 and gear 5 in the manner above described. The reverse rotation of the pinion and gear takes 80 place while the pawl 7' is moving downwardly and then upwardly preparatory to its next engagement with the pinion. This period of time, during which the pawl 7' is out of engagement with its pinion, is just 85 sufficient to permit the action of the weight upon the parts operated thereby. And by the time the action of the weight has been completed, the pawl 7' has moved upwardly to the point to engage the pinion and cause 90 the next intermittent advance movement. In other words, the operation effected by the weight is performed during the regular idle interim of the pawl 7' and the regular 95 operation of the machine is not interrupted or interfered with by the operation of this indicating device.

Assuming that each of the particular books to be sewed comprises forty sections, the pin 20 is spaced from the cam member 100 36 a distance corresponding to forty teeth of the gear 5, and the device is set so that upon inserting the first section in the machine, the gear 5 will be moved the distance of the first tooth. Upon inserting the second section, the gear 5 will be moved the distance of the second tooth, and so on, the parts operating in the manner above explained. Then upon inserting the fortieth section, the gear will be moved the distance 105 corresponding to the fortieth tooth; whereupon the tripping mechanism will be actuated, as above explained, and the bell will ring to indicate that the group of sections fed into the machine contains the proper 110 number. Should, however, the bell ring before the operator has fed all of the sections of a group into the machine, he will then know that the group contains too many sections and that this particular book, as sewed 115 up to that point, should be removed. This is done by stopping the machine. Or, if the bell should not ring when all of the sections of a given group have been fed into the machine, then the operator will know that 120 that particular group contains too few sections, and the machine is then stopped by the operator so as to remove this imperfect book.

If the operator prefers, he may advance 125 the gear 5 one tooth at the beginning of the 130

day so as to have the bell ring, under normal conditions, just after he places the next to the last section of a given group in the machine, or in other words, just as he is 5 about to insert the last section. In this way, the operator has a little advance notice that that particular group of sections contains the proper number, he being able to observe, of course, that the section which he is about 10 to insert is the last of that group. In case the bell should not ring at this particular time, the operator knows that he should stop the machine; and, when so set, he has more time to act so as to preclude the mistake of 15 starting on the next group without first removing the imperfect book.

Then, too, should the operator discover that one or more sections are imperfect, after 20 they have been fed into the sewing machine, and after they have been registered by my present device, he will stop the machine, remove the imperfect section or sections, replace such sections in the stack, and turn the gear 5 back a number of teeth corresponding to the number of sections replaced. 25 Then the operator resumes operation and the device is in step with the number of sections in the stack. It is obvious that, except for the reverse re-setting movement of the gear 5, in such a case as just referred to, the bell would ring before all the sections are fed 30 into the machine. The extent of such reverse adjustment is limited only by the position of the trip pin 20, as will be understood 35 by referring to the drawing.

The advantages resulting from my present attachment will be obvious. With this device, the operator is enabled to know whether the successive groups of sections contain the 40 proper number; and if not, an opportunity is afforded to prevent an imperfect book from passing. Furthermore, my device is not only automatic in its action, but it can be attached to the present form of book-sewing machine, or the like, without requiring alteration thereof. And, too, the trip means 45 20 is adjustable so that the device can be set according to the number of sections in a particular book that is to be sewed. 50 Another advantage resides in the ability to reverse or re-set the gear 5 whenever necessary to keep the device in proper step. Other advantages will readily suggest themselves to one who is familiar with the art. 55

What I claim as new is:

1. In a book-sewing machine, the combination of means for receiving and securing together a succession of sections, and means, operated automatically by said first-named 60 means, for indicating successive equal groups of such sections.

2. In a book-sewing machine, the combination of means for receiving and securing together a succession of sections, and means, adapted for removable attachment to and

for operation automatically by said first-named means, for indicating succeeding equal groups of such sections.

3. In a book-sewing machine, the combination of means for receiving and sewing together a succession of sections, and means, operated automatically by said first-named means, for indicating successive groups of sections, each containing the same predetermined number, and said indicating means 75 being adjustable according to the number of such sections in a given group.

4. In a device of the class described, the combination of means for receiving and treating a succession of articles, indicating 80 means adapted to be cocked and released, means controlled by said first-named means for automatically cocking said indicating means upon treatment of a predetermined number of such articles, and means for then 85 automatically causing instantaneous release and operation of said indicating means.

5. In a device of the class described, the combination of means, including a reciprocating part, for receiving and treating a succession of articles, a signalling means 90 adapted to be cocked and released, means including a movable part adapted for actuation in one direction by said reciprocating part for cocking said signalling means, and 95 means for then automatically actuating said movable part in the reverse direction so as to effect release and operation of the signalling means.

6. In a device of the class described, the combination of means, including a reciprocating part, for receiving and treating a succession of articles, a signalling means adapted to be cocked and released, means including a movable part adapted for actuation in one direction by said reciprocating part for cocking said signalling means, and 100 means for automatically actuating said movable part in the reverse direction so as to effect release and operation of the signalling 105 means, said actuating means being initiated in its operation by the operation of said cocking means.

7. In a device of the class described, the combination of means, including a reciprocating part, for receiving and treating a succession of articles, a signalling means adapted to be cocked and released, means including a movable part adapted for actuation in one direction by said reciprocating part for cocking said signalling means, means tending to move said movable part in the reverse direction so as to operate the signalling means, means for restraining said last-named means and means for automatically releasing the movable part from said restraining means when a predetermined number of articles has been treated, thereby causing release and operation of the signalling means. 110 115 120 125 130

8. In a device of the class described, the combination of means, including a reciprocating part, for receiving and treating a succession of articles, said reciprocating part being active only in one direction, an indicating means, and automatic means controlled by said reciprocating part for operation of said indicating means, said parts being so constructed and arranged that the 10 operation of said indicating means is effected during the interim between successive active movements of the reciprocating part.

9. An indicating attachment for book sewing machines or the like, comprising a 15 bracket adapted to be attached to the frame of the machine, a signalling means, an arm for actuating said signalling means, and means for operating said arm, all of said parts being mounted upon said bracket, and 20 said operating means being adapted for automatic control by a moving part of such machine.

10. An indicating attachment for book sewing machines or the like, comprising a 25 bracket adapted to be attached to the frame of the machine, a signalling means, an arm adapted to actuate said signalling means, means tending to cause said arm to actuate said signalling means, a detent for holding 30 said arm in idle position, all of said means being carried by said bracket, and automatic means governed by the operation of the machine for intermittently releasing said arm from said detent so as to produce a signal.

11. An indicating attachment for book sewing machines or the like, comprising a 35 bracket adapted to be attached to the frame of the machine, a signalling means, an arm adapted to actuate said signalling means, means tending to cause said arm to actuate 40 said signalling means, means for temporarily withholding said signalling means from operation, and means for automatically releasing said withholding means repeatedly at regular intervals, all of said parts being 45 supported upon said bracket and being adapted to be controlled by the operation of the machine to which attached.

12. An indicating attachment for book sewing machines or the like, comprising a 50 bracket adapted to be attached to the frame of the machine, a signalling means, an arm adapted to actuate said signalling means, means tending to cause said arm to actuate 55 said signalling means, automatic means for temporarily withholding said signalling means from operation, and means for automatically releasing said withholding means repeatedly at regular predetermined intervals, all of said parts being mounted upon 60 said bracket and being adapted to be controlled by the operation of the machine to which attached.

13. An indicating attachment for book 65 sewing machines or the like, comprising a

bracket adapted to be attached to the frame of the machine, a signalling means, an arm adapted to actuate said signalling means, means tending to cause said arm to actuate said signalling means, adjustable automatic 70 means for temporarily withholding said signalling means from operation, and means for automatically releasing said withholding means at regular predetermined intervals, all of said parts being mounted upon said 75 bracket and being adapted to be controlled by the operation of the machine to which attached.

14. An indicating attachment for book sewing machines or the like, comprising a 80 bracket adapted to be attached to the frame of the machine, a signalling means, a rockably mounted arm adapted to actuate said signalling means, means tending to cause said arm to actuate said signalling means, withholding means adapted to be automatically set by operation of the machine after a predetermined period, and means automatically set into operation by actuation of said withholding means for releasing the same so as 90 to effect operation of the signalling means, all of said parts being mounted upon said bracket and being adapted for control by the operation of the machine to which attached.

15. An indicating attachment for book sewing machines or the like, comprising a signalling means adapted to be cocked and released, means adapted for movement in one direction for cocking the signalling means and in the reverse direction for effecting release and operation of the same, and means adapted for co-ordination with a moving part of the machine to which attached for automatic control of said movable means at regular intervals.

16. An indicating attachment for book sewing machines or the like comprising a signalling means adapted to be cocked and released, rotatable means adapted for movement in one direction for first cocking 110 and later recocking the signalling means and in the reverse direction for effecting release and operation of the same, and means adapted for co-ordination with a moving part of the machine structure, to which the device is 115 attached, for automatic control of said rotatable means at regular intervals.

17. An indicating attachment for book sewing machines or the like comprising a signalling means, rotatable means adapted for movement in one direction for cocking the signalling means and in the reverse direction for effecting operation of the same, and adjustable means carried by said rotatable means for varying the movements 120 thereof with respect to time, said rotatable means being adapted for coordination with the movable part of the machine structure for automatic operation thereby at regular 125 intervals.

18. An indicating attachment comprising a signalling means, an arm mounted for rockable movement in one direction for cocking the same and in another direction for operating said signalling means, a spring operatively arranged with respect to said arm so as to afford actuating force therefor to hold said arm in cocked position and to cause actuation of said signalling means, a rotatable member adapted for movement in one direction to cock said arm and in the opposite direction to release said arm so as to permit operation of said signalling means, and means adapted for operation by a machine structure for actuating said rotatable member in one direction, and automatic means for actuating said rotatable member in the other direction.

19. An indicating attachment for book sewing machines or the like comprising a signalling means, rotatable means adapted for movement in one direction for first cocking and at any time thereafter re-cocking the signalling means, means for effecting operation of said rotatable means; in the reverse direction for effecting operation of the signalling means, and means adapted for coordination with a moving part of the machine structure, to which the device is attached, for automatic control of said rotatable means at regular intervals.

20. An indicating attachment comprising a signalling means, an arm mounted for movement in one direction for cocking and in another direction for operating said signalling means, means for holding said arm in cocked position and for causing actuation of said signalling means upon release thereof, means adapted for movement in one direction to cock said arm and in the opposite direction to release said arm so as to permit operation of said signalling means, means adapted for operation by a machine structure for actuating said last-named movable means in one direction, and automatic means for actuating said last-named movable means in the other direction.

21. An indicating attachment comprising a signalling means, an arm mounted for rockable movement in one direction for cocking the same and in another direction for operating said signalling means, means operatively arranged with respect to said arm so as to afford actuating force therefor to hold said arm in cocked position and to cause actuation of said signalling means, a rotatable toothed member adapted for movement in opposite directions, means carried by said rotatable member for cocking said arm when said member is rotated in one direction, means carried by said rotatable member for releasing said arm so as to permit operation of said signalling means when said member is rotated in the opposite direction, means adapted for operation by a ma-

chine structure for engaging the teeth of said rotatable member in one direction, so as to rotate the same step by step, means for engaging the teeth of said rotatable member for temporarily preventing movement of said rotatable member in the opposite direction until said arm is cocked, means for releasing said preventing means simultaneously with the cocking of the signalling means and automatic means for actuating said rotatable member in the other direction upon release of said preventing means so as to permit actuation of the signalling means.

22. An indicating attachment comprising a signalling means, an arm mounted for movement in one direction for cocking and in another direction for operating said signalling means, means for holding said arm in cocked position and for causing actuation of said signalling means upon release thereof, means adapted for movement in one direction to cock said arm and simultaneously to become free for reverse movement to release said arm, means adapted for operation by a machine structure for actuating said last-named movable means in one direction, and automatic means for actuating said last-named movable means in reverse direction, upon release of the same, thereby effecting release of said arm and operation of the signalling means.

23. An indicating attachment comprising cooperating parts of a signal device, one of said parts being movable towards and away from the other part for cooperation therewith and being movable also in another direction for cocking of the same, a rotary toothed wheel, means actuated by the machine to which the attachment is applied, for rotating said wheel in one direction, a locking pawl therefor, said movable part of the signal device having a first portion extending to one side of said wheel and having a second portion associated with said pawl for disengagement thereof, a detent for said movable part for locking the same, means carried by said wheel and adapted for engagement with the said first portion of said movable part to cock the same and at the same time to cause disengagement of the pawl by said second portion, means for maintaining said movable part in engagement with said detent and also for forcing the movable part into engagement with the other part of the signalling device upon release thereof, means for rotating said wheel in the reverse direction upon release of said pawl, and a cam means carried by said wheel for engagement with said first portion, upon reverse operation of said wheel, so as to release said movable part of the signalling device from the detent and permit the signalling device to be operated.

In testimony whereof I affix my signature.
HERMAN S. CAHEN.
